BREAD SLICING MACHINE

Harry J. Criner, Davenport, Iowa, assignor of
one-half to A. G. Bush, Davenport, Iowa

Application January 5, 1933. Serial No. 650,260

17 Claims. (Cl. 146—153)

My invention relates to improvements in bread slicing machines of the general type shown in my co-pending application Serial No. 636,459, in which blades having a reciprocating stroke actuated at least in one direction by a rocker arm, are utilized.

The objects of my invention are:

1. To provide a slicing machine in which two series of blades reciprocate alternately and have their cutting edges maintained substantially in the same plane;

2. To provide a slicing machine in which the cutting blades may be reciprocated by a rocker arm and the cutting edges maintained in substantially the same plane;

3. To provide means which will permit a relatively long stroke of cutting blades actuated by a rocker arm without materially deflecting the cutting edges of the blade from a given plane of operation;

4. To provide means for driving a reciprocating blade or other part by a rocker arm and for maintaining it constantly in a given line of travel longitudinally while being so driven;

5. To provide a simple, practical form of reciprocating slicing machine which will reduce vibration to a minimum;

6. To provide a balanced straight line drive for alternatingly reciprocating sets of longitudinally moving parts.

I accomplish these objects by the means illustrated in the accompanying drawings, in which—

Figure 1 is a side elevation of my machine on the line 1—1 of Figure 2;

Figure 2 is a vertical section of my machine on the line 2—2 of Figure 1;

Figure 3 is an enlarged detail plan view showing a portion of the crossbars and rocker arms in section;

Figure 4 is a normal size sectional detail on the line 4—4 of Figure 3.

Similar numerals refer to similar parts throughout the several views.

My machine comprises a frame, 1, having feet, 1a, comprising side frames suitably united by cross-members which may be either separate or formed integral therewith.

Upon the frame near one end thereof I mount a housing, 21, preferably formed of a deep metal channel suitably secured to the frame by bolts, rivets or other means and with end plates, 22 and 22a, on either side thereof suitably secured by bolts or rivets, 22b, to the housing, 21.

I mount a pair of short shafts, 40, in suitable bearings, 40a, formed on opposite sides of the

main frame. Upon each shaft, 40, I mount just inside of the frame, a rocker arm, 38. These rocker arms are pivotally mounted upon the shafts, 40, and have crossbars, 38a, formed integral therewith or suitably secured thereto. I prefer to cast the rocker arms 38, and the cross-bars, 38a, in one piece. Each rocker arm, 38, has a hub, 39, formed integral therewith at the middle thereof and hubs, 41, cast integral therewith at the opposite ends thereof. The hubs, 39, are preferably provided with ball-bearings mounted upon the shafts, 40, so as to rotate freely thereon.

In each of the hubs or bosses, 41, I mount an oilless bearing, 42. Drive bars for the cutting blades are formed of cross-members, 44, each cross-member having a bracket, 43, cast integral therewith at each end thereof and in the brackets, 43, pins, 42a, are rigidly secured which extend into and are pivotally mounted in the bearings, 42. Each drive bar, 44, has a plurality of lugs, 48, formed upon the inner face thereof, with a slot or opening, 48a, cut in each lug to permit the introduction of a cutting blade therein.

The cutting blades may be secured to the lugs by pivot pins, 25a, secured in the lower ends of the blades and seated in suitable bores or grooves in the lugs, 48. The lower end of each bracket, 43, has a hardened steel plate, 45, secured upon the inner face thereof by set screws, 44a. In each side frame of the machine adjacent the lower ends of the brackets, 43, I mount a pivot pin or stub shaft, 47, carrying a ball-bearing, 46. These ball-bearings, 46, and the inner faces of the lower ends of the brackets, 43, are so proportioned and located that the hardened plates, 45, will form a contact with the adjacent faces of the roller bearings and as the rocker arm, 38, oscillates, the steel plates, 45, will run up and down upon the adjacent ball-bearings, 46, thereby largely doing away with any friction.

I attach the lower ends of a plurality of cutting blades, 25, to the lugs, 48, as heretofore described, these blades being arranged in two series, one series being attached to the lugs upon the front drive bar, 44, and the other series being attached to the lugs upon the rear drive bar, 44. These cutting blades extend upwardly through a plate or feed table, 16, having slots or openings, 28, cut therein through which the blades may pass, and the upper ends of the blades, 25, are attached to the lower ends of springs, 23, the upper ends of which project upwardly through the housing 21, and are threaded to receive and be secured in place by nuts, 24, by which the ten-

sion upon the cutting blades may be individually adjusted.

I mount oilless guide or bearing blocks, 26, within the housing, 21, said guide-bars being provided with slots through which the blades severally pass, the sides of the slots acting as guides for the blades.

I prefer to form this guide-bar, 26, of some graphited bearing metal, but it is obvious that 10 oiled maple or any other suitable material may be used. The guidebars, 26, are mounted in an angleiron, 27, the ends of which may be secured to the sides of the housing, 21, by rivets or bolts.

In order to oscillate the rocker arms, 38, I form 15 integral with one of the crossbars, 38a, an arm, 38b, preferably near the middle of the crossbar, having a suitable bearing, 36, formed therein. A connecting rod, 32, has its upper end, 35, forked to embrace the bearing in the arm, 38b, of the 20 connecting rod, 32, with a pivot, 37, rigidly secured in the fork, and pivotally mounted in the bearing, 36. The opposite end, 33, of the connecting rod is pivotally mounted upon a crank pin, 34, with an oilless bearing, 34a, interposed 25 between them. This crank pin is rigidly united to a fly wheel, 29, which revolves upon a shaft, 31b, mounted in oilless bearings, 31a, secured in the bracket, 31, formed integral with the frame.

The fly wheel, 29, has its periphery grooved to 30 carry a belt, 4, by which it is driven from a motor pulley, 3, mounted upon the shaft of the motor, 2. The motor, 2, has its feet, 2a, mounted upon the frame, 1, preferably with a pad, 1b, interposed to reduce vibration.

35 Supports, 5, united by a crossbar, 5a, extend upwardly from the frame at the left or front of the machine and have mounted in the upper end thereof a conveyor shaft, 8, upon which a roll, 7, is secured which carries a conveyor belt, 6.

40 A similar roll, 7a, is mounted upon a similar shaft, 8a, secured in the frame adjacent the bread plate, 16, and the conveyor belt, 6, passes over both rolls and carries the bread toward the blades.

45 Lateral guides, 9, are secured to the uprights, 5, by bolts, 9a, and serve to keep the bread from lateral displacement in its passage to the blades.

A similar conveyor belt, 10, is mounted at the rear of the machine to carry the bread away after 50 it is cut and passes over a roll, 11, mounted upon the shaft, 14, which is pivotally mounted in suitable bearings formed in brackets, 15, which may be attached to the table, 16, by rivets or other suitable means. An extension, 13, may be 55 formed integral with the bracket, 15, to carry the lower conveyor roll of the take-off conveyor, but is not shown in the drawings as any desired type of conveyor may be used with this slicing machine.

60 Guide rails, 12, are secured to the frame by bolts, 12a, adjacent the conveyor belt, 10.

While I have shown each individual blade attached to and actuated in one direction by a tension spring and in the other direction by the drive bars, I do not limit my claims to this precise construction. It is obvious that any form of attachment for the upper ends of the blades may be used which will carry them in a straight line longitudinally and that the upper ends of the blades 65 may be driven by duplicates of the driving apparatus for the lower ends if desired without departing from the spirit of my invention.

In practice it is found desirable to actuate the cutting blade longitudinally in such a way as to 70 keep all cutting edges in a given vertical plane

and to actuate such blades by rocker-arms for the purpose of reducing vibration and to simplify the drive thereof.

In order to cut bread with considerable rapidity, it is necessary that a long stroke be given to 80 the cutting blades. The use of rocker arms as heretofore designed, has prevented the blades from traveling in straight lines but the driving mechanism I have shown causes the lower ends of the blades to travel at all times both during the upward and downward stroke in straight lines and with the pivots in the lower ends of the blades all secured in line transversely of the machine, they will cause all of the blades to travel in the same vertical planes. The springs attached to the upper ends of the blades have a 85 direct vertical pull and will tend to hold the blades in line vertically at all times. If desired, the blades of one series may be given a lead over the other series by advancing one of the drive bars and arranging the spring of the first series to correspond.

The pull of the springs upon the blades will hold the lower ends of the brackets, 43, as far 90 inward as the ball-bearings, 46, and the hardened plates, 45, will permit. The outer casing of the ball-bearing will act as detent to prevent the hardened plates, 45, and the brackets attached thereto, from being carried out of line inwardly.

In the operation of my machine, the parts are 95 assembled as described above, and the motor started. The bread to be sliced is placed upon the conveyor, 6, which is driven by a pulley, 49, that may be belted to the motor, 2, or to any independent source of power. The revolution of the fly 100 wheel, 29, causes the rocker arms, 38, to oscillate upon their shafts, 40. As one end of the rocker-arm, 38, travels downwardly, it carries its attached bracket, 43, downwardly, thus driving the attached lugs, 48, and the blades, 25, secured thereto, in a downward direction. As the fly wheel, 29, completes its revolution, it drives the connecting 105 rod, 22, upwardly and reverses the action of the rocker arm, 38, carrying the opposite series of lugs and attached blades downwardly, and this 110 reciprocating action is repeated as long as the motor runs.

The blades are propelled upwardly by the upward motion of the lugs to which they are attached and, at the same time, are drawn upwardly 115 by the tension of the springs attached thereto so as to give them a reciprocating action through the bread and each blade makes its appropriate slicing cut, the blades, of course, being spaced at the desired distance apart. The tension of the 120 springs is sufficient to keep the blades taut at all times and to permit the use of very thin blades.

I prefer to form the blades with a toothed cutting edge, but the cutting edge may be straight or sinuate if desired.

135 It is obvious that various changes may be made in the size, proportions and position of the various parts of my apparatus and that it may be adapted to cut various things, without departing from the spirit of my invention and I do not 140 confine my claims to the precise forms shown in the drawings.

I claim:

1. In a slicing machine having a frame and a plurality of slicing blades mounted therein, an actuating mechanism for the blades comprising an opposed pair of spaced rocker-arms pivoted in the frame, an opposed pair of brackets pivotally mounted upon each of the rocker-arms, drive bars uniting the corresponding brackets laterally, a plurality 145

of lugs united to the drive bars, means for severally attaching one end of the blades to the lugs, and means for oscillating the rocker-arms.

2. In a slicing machine having a frame and a plurality of slicing blades mounted therein, an actuating mechanism for the blades comprising a pair of spaced rocker-arms united by cross-bars and pivoted in the frame, an opposed pair of brackets pivotally mounted upon each of the 10 rocker-arms, drive bars uniting the corresponding brackets laterally, a plurality of lugs united to the drive bars, means for severally attaching one end of the blades to the lugs, and means for oscillating the rocker-arms.

15 3. In a slicing machine having a frame and a plurality of slicing blades mounted therein, an actuating mechanism for the blades comprising a pair of spaced rocker-arms pivoted in the frame, an opposed pair of brackets pivotally mounted upon each of the rocker-arms, drive bars uniting the corresponding brackets laterally, a plurality of lugs united to the drive bars severally, means attaching one end of the blades to the lugs, bearing blocks united respectively to the free ends of the brackets, rolls pivotally mounted in the frame adjacent the bearing faces and interposed respectively between the opposed bearing blocks, and means for oscillating the rocker-arms.

4. In a slicing machine having a frame and a plurality of slicing blades mounted therein, an actuating mechanism for the blades comprising a pair of spaced rocker-arms united by cross-bars and pivoted in the frame, an opposed pair of brackets pivotally mounted upon each of the 35 rocker-arms, drive bars uniting the corresponding brackets laterally, a plurality of lugs united to the drive bars severally, means attaching one end of the blades to the lugs, bearing blocks united respectively to the free ends of the brackets, rolls pivotally mounted in the frame adjacent the bearing faces of the brackets, and means for oscillating the rocker-arms.

5. In a slicing machine having a frame and a plurality of slicing blades mounted therein, an actuating mechanism for the blades comprising a pair of spaced rocker-arms pivoted in the frame, an opposed pair of brackets pivotally mounted upon each of the rocker-arms, drive bars uniting the corresponding brackets laterally, a series of lugs united to each of the drive bars severally, means pivotally attaching one end of the blades to the lugs, bearing blocks united respectively to the free ends of the brackets, detents mounted in the frame and interposed respectively between the opposed bearing blocks, and means for oscillating the rocker-arms.

6. In a slicing machine having a frame and a plurality of slicing blades mounted therein, an actuating mechanism for the blades comprising a pair of spaced rocker-arms pivoted in the frame, an opposed pair of brackets pivotally mounted upon each of the rocker-arms, drive bars uniting the corresponding brackets laterally, a series of lugs united to each of the drive bars severally, means pivotally attaching one end of the blades to the lugs, tension springs attaching the other end of the blades severally to the frame and adapted to exert a continuous tension upon the blades, bearing blocks united respectively to the free ends of the brackets, detents mounted in the frame and interposed respectively between the opposed bearing blocks, and means for oscillating the rocker-arms.

7. In a slicing machine having a frame and

a plurality of slicing blades mounted therein, an actuating mechanism for the blades comprising a pair of spaced rocker-arms pivoted in the frame, an opposed pair of brackets pivotally mounted upon each of the rocker-arms, drive bars uniting the corresponding brackets laterally, a series of lugs united to each of the drive bars severally, means pivotally attaching one end of the blades to the lugs, bearing inner faces formed upon the free ends of the brackets, detents mounted in the frame and interposed respectively between the opposed bearing faces, and means for oscillating the rocker-arms.

8. A slicing machine comprising a frame, spaced rocker-arms pivoted in the frame on opposite sides thereof respectively, cross-bars united to the rocker-arms, a bracket pivotally mounted upon each of the rocker-arms in corresponding positions near corresponding ends thereof, a transverse drive bar united to the brackets, a plurality of lugs united to the drive bar, means for severally attaching one end of the blades to the lugs, bearing faces formed respectively upon the free ends of the brackets, rolls pivotally mounted in the frame adjacent the bearing faces of the brackets, and means for oscillating the rocker-arms.

9. A slicing machine comprising a frame, spaced rocker-arms pivoted in the frame on opposite sides thereof respectively, cross-bars united to the rocker-arms, a pair of opposed brackets pivotally mounted upon each of the rocker-arms in corresponding positions at or near the ends thereof, transverse drive bars united to the corresponding brackets of each pair respectively, a plurality of lugs united to the drive bars, means for severally attaching one end of the blades to the lugs, bearing faces united respectively to the free ends of the brackets, rolls pivotally mounted in the frame adjacent the bearing faces of the brackets, and means for oscillating the rocker-arms.

10. A slicing machine comprising a frame, spaced rocker-arms pivoted in the frame on opposite sides thereof respectively, cross-bars united to the rocker-arms, a pair of opposed brackets pivotally mounted upon each of the rocker-arms in corresponding positions at or near the ends thereof, transverse drive bars united to the corresponding brackets of each pair respectively, a plurality of lugs united to the drive bars, means for severally attaching one end of the blades to the lugs, bearing faces united respectively to the free ends of the brackets, detents mounted in the frame adjacent the bearing faces of the brackets, and means for oscillating the rocker-arms.

11. A slicing machine comprising a frame, spaced rocker-arms pivoted in the frame on opposite sides thereof respectively, cross-bars united to the rocker-arms, a pair of opposed brackets pivotally mounted upon each of the rocker-arms in corresponding positions at or near the ends thereof, transverse drive bars united to the corresponding brackets of each pair respectively, a plurality of lugs united to the drive bars, means for severally attaching one end of the blades to the lugs, tension springs attaching the other end of the blades severally to the frame and adapted to exert a continuous tension upon the blades, bearing faces united respectively to the free ends of the brackets, detents mounted in the frame adjacent the bearing faces of the brackets, and means for oscillating the rocker-arms.

12. A slicing machine comprising a frame, spaced rocker-arms pivoted in the frame on op-

posite sides thereof respectively, cross-bars united to the rocker-arms, a bracket pivotally mounted upon each of the rocker-arms in corresponding positions near corresponding ends thereof, a transverse drive bar united to the brackets, a plurality of lugs united to the drive bar, means for severally attaching one end of the blades to the lugs, bearing faces formed respectively upon the free ends of the brackets, rolls pivotally mounted in the frame adjacent the bearing faces of the brackets, means for oscillating the rocker-arms, and means for supporting the article being sliced while passing the blades.

13. A slicing machine comprising a frame, spaced rocker-arms pivoted in the frame on opposite sides thereof respectively, cross-bars united to the rocker-arms, a bracket pivotally mounted upon each of the rocker-arms in corresponding positions near corresponding ends thereof, a transverse drive bar united to the brackets, a plurality of lugs united to the drive bar, means for severally attaching one end of the blades to the lugs, bearing faces formed respectively upon the free ends of the brackets, rolls pivotally mounted in the frame adjacent the bearing faces of the brackets, means for oscillating the rocker-arm, and means for supporting and feeding the article to be sliced during the slicing operation.

14. A slicing machine comprising a frame, spaced rocker-arms pivoted in the frame on opposite sides thereof respectively, cross-bars united to the rocker-arms, a pair of opposed brackets pivotally mounted upon each of the rocker-arms in corresponding positions at or near the ends thereof, transverse drive bars united to the corresponding brackets of each pair respectively, a plurality of lugs united to the drive bars, means for severally attaching one end of the blades to the lugs, bearing faces united respectively to the free ends of the brackets, rolls pivotally mounted in the frame adjacent the bearing faces of the brackets, means for oscillating the rocker-arms, and means for supporting and feeding the article to be sliced during the slicing operation.

15. A slicing machine comprising a frame, spaced rocker-arms pivoted in the frame on opposite sides thereof respectively, cross-bars united to the rocker-arms, a pair of opposed brackets pivotally mounted upon each of the rocker-arms in corresponding positions at or near the ends thereof, transverse drive bars united to the corresponding brackets of each pair respectively, a plurality of lugs united to the drive bars, means for severally attaching one end of the blades to the lugs, bearing faces united respectively to the free ends of the brackets, rolls pivotally mounted in the frame adjacent the bearing faces of the brackets, a slotted table interposed between the drive bars and the springs with the blades passing through the slots therein, and means for oscillating the rocker-arms.

brackets pivotally mounted upon each of the rocker-arms in corresponding positions at or near the ends thereof, transverse drive bars united to the corresponding brackets of each pair respectively, a plurality of lugs united to the drive bars, means for severally attaching one end of the blades to the lugs, bearing faces united respectively to the free ends of the brackets, detents mounted in the frame adjacent the bearing faces of the brackets, means for oscillating the rocker-arms, and means for supporting and feeding the article to be sliced during the slicing operation.

16. A slicing machine comprising a frame, spaced rocker-arms pivoted in the frame on opposite sides thereof respectively, cross-bars united to the rocker-arms, a pair of opposed brackets pivotally mounted upon each of the rocker-arms in corresponding positions at or near the ends thereof, transverse drive bars united to the corresponding brackets of each pair respectively, a plurality of lugs united to the drive bars, means for severally attaching one end of the blades to the lugs, bearing faces united respectively to the free ends of the brackets, rolls pivotally mounted in the frame adjacent the bearing faces of the brackets, a slotted table interposed between the drive bars and the springs with the blades passing through the slots therein, and means for oscillating the rocker-arms.

17. A slicing machine comprising a frame, spaced rocker-arms pivoted in the frame on opposite sides thereof respectively, cross-bars united to the rocker-arms, a pair of opposed brackets pivotally mounted upon each of the rocker-arms in corresponding positions at or near the ends thereof, transverse drive bars united to the corresponding brackets of each pair respectively, a plurality of lugs united to the drive bars, means for severally attaching one end of the blades to the lugs, bearing faces united respectively to the free ends of the brackets, rolls pivotally mounted in the frame adjacent the bearing faces of the brackets, a slotted table interposed between the drive bars and the springs with the blades passing through the slots therein, conveyors to carry the bread to and from the slotted table, and means for oscillating the rocker arms.
